Inventor

Antonio S. Hernandez

By Norman J. Whitaker
his Attorney

UNITED STATES PATENT OFFICE.

ANTONIO S. HERNANDEZ, OF GUBAT, SORSOGON, PHILIPPINE ISLANDS.

HEMP-SHREDDING DEVICE.

Application filed April 2, 1921. Serial No. 457,961.

To all whom it may concern:

Be it known that I, ANTONIO S. HERNANDEZ, a citizen of the United States and a resident of Gubat, in the Province of Sorsogon, Philippine Islands, have invented a new and useful Hemp-Shredding Device, of which the following is a specification.

My invention is a hemp shredding device and has as its principal object the provision of a device of this character which may be regulated to shred the hemp fibre to any desired degree of fineness.

Further the invention provides a portable hemp shredding device which can be readily taken down and carried to any desired part of the field and set up for operation.

It is a further object of the invention to provide a hemp shredder which embodies a scraping or shredding blade yieldably held into engagement with the hemp to be shredded, the latter being so arranged as to permit the blade to be held against the fibre with any degree of pressure to shred the fibre into fine or coarse shreds as desired.

Another object of the invention provides a portable hemp fibre shredding device which employs a pivoted scraper blade which is held against the fibre by a spring element under tension, the tension of which may be varied whereby the fibre will be shredded to the desired degree.

With the preceding and other objects and advantages in mind, the invention consists in the novel combination of elements, construction and arrangement of parts and operations which will be hereinafter enlarged upon, claimed and illustrated in the accompanying drawings, wherein:

40 Figure 1 is an elevation of the device in operation;

Figure 2 is a view taken on line 2—2 of Figure 1;

Figure 3 is a vertical sectional view taken 45 on line 3—3 of Figure 1;

Figure 4 is a similar view taken on line 4—4 of Figure 1;

Figure 5 is a fragmentary elevation of the device;

50 Figure 6 is an enlarged detail view of the scraper blade and its mounting; and

Figure 7 is a modified form of tension device embodied in the invention.

Referring in detail to the drawings

wherein like characters of reference designate like parts throughout the several views, the numeral 5 denotes a pair of vertical uprights upon which a supporting bracket 6 is detachably supported. This supporting bracket is of U-shape and the legs thereof terminate in hooks 7 which embrace the upper ends of the uprights 5. Set screws 8 are carried by the ends of the U-shaped bracket and engage the uprights to hold the bracket in place thereon. Extending vertically from one of the hooks 7 is a shank 9 and arranged in spaced relation thereto in transverse alignment on this hook is an upstanding pin 10.

A work block, designated at 11, has one end disposed between the shank 9 and pin 10 while its opposite end is held in place by a bolt 12 carried by the adjacent part of the frame or supporting bracket 6 and passing through this end of the block, a wing nut 13 being threaded on this bolt. The shredding or scraping knife is designated in its entirety at 14. This knife is provided with cutting edges 15, each of which is of a different degree of sharpness. The knife 14 is provided with a channel shaped member 16 in which one end of a relatively long resilient bar 17 is secured.

Embracing the shank 9 is a clamp 18 formed with an outstanding pivot 19 passing through the knife 14 at its approximate center. A wing nut 20 is threaded on the pivot 19 to hold the knife 14 against lateral movement. Supported on the shank 9 is a vertical pole 21 to the upper end of which a flexible element 22 is attached. There is provided a tension device whereby the pressure of the scraper blade 14 may be varied which consists of a stirrup 23 having its ends pivotally connected with the free end of the resilient bar 17 as at 24. A turn-buckle 25 is engaged with the stirrup 23 and carries a ring 26 at its opposite end to which the lower end of the flexible element 22 is attached. This turn-buckle is formed with an eye 27 in which a hand-grip may be engaged to operate the turn-buckle to regulate the tension of the resilient bar 17.

Suspended from the resilient bar 17 in proximity to the channel shaped member 16 is a flexible element 28, the lower end of which is attached to a treadle 29, one end of which is fulcrumed by upstanding stakes 30.

Normally the free end of the treadle 29 is disposed above the ground and is adapted to be rocked downwardly as shown in Figure 1 to move the scraper blade 14 away from the block 11.

In operation the hemp is placed upon the block 11 and the treadle actuated to flex the bar 17 which causes the knife 14 to move on its pivot away from the block 11. Upon releasing the treadle the resilient bar 17 upon returning to its normal position, returns the scraper blade or knife and holds the same under tension against the hemp which is then drawn between the block 11 and the cutting edge of the knife.

In Figure 7 a modified embodiment of tension regulating device is shown and includes a substantially elliptical frame 31 having guide openings 32 at its opposite ends. A flexible element 33 is secured to one end of the frame and its opposite end adapted for connection to the upper end of the pole 21. A second flexible element 34 is passed through the guide opening 32 at the opposite end of the frame and is adapted to be connected with the free end of the resilient bar 17. A stem 35 is journaled in the frame at its center to which the inner end of the flexible element 34 is attached and is adapted to be wound therearound. One end of the stem 35 is formed with an eye 36 in which a handle 37 is engaged. The flexible element 33 is provided with a loop 38 adapted to engage one end of the handle 37 after the stem has been operated to wind the flexible element 34 on the stem 35 to hold the stem against rotation.

It is to be understood that the forms of my invention herein shown and described are to be taken as preferred examples of the same, and that various changes in the shapes, sizes and arrangement of parts may be resorted to without departing from the spirit of the invention or the scope of the subjoined claims.

Having thus described my invention, what I claim as new and desire to secure and protect by Letters Patent of the United States, is:

50 1. In a hemp shredder, a supported work block, a scraper blade pivoted above the block to swing toward and away from the same, a resilient bar connected to one end of the scraper blade, means for suspending one end of the resilient bar, and means for flexing the bar whereby to move the scraper blade away from the block, the bar upon returning to its normal position moving the scraper blade toward the block and holding the same under tension against the latter.

60 2. A device of the character described comprising a supported work block, a scraper blade pivoted above the block to swing about a horizontal axis, a horizontally arranged resilient bar having one end secured to the

scraper blade and its opposite end supported, and means for flexing the bar whereby to swing the scraper blade away from the work block, the scraper blade being swung into engagement with the block and held under tension thereagainst upon the return of the bar to its normal position.

70 3. A device of the character described comprising a supported work block, a scraper blade pivoted above the block to swing about a horizontal axis, a horizontally arranged resilient bar having one end secured to the scraper blade and its opposite end supported, and a treadle connected with the bar adapted to be moved downwardly to flex the bar whereby to swing the scraper blade away from the block, the scraper blade being returned to normal position upon release of the treadle.

75 4. In a device of the character described, a work block, a pivoted scraper blade disposed above the block to be swung toward and away from the latter, a resilient bar having one end rigidly attached to one end of the scraper blade, a suspended flexible element connected with the free end of the resilient bar, and means for manually flexing the bar to swing the scraper blade away from the block, the scraper blade being moved into engagement with the block and resiliently held thereagainst upon release of said means.

80 5. A device of the character described comprising a work block over which material to be shredded is adapted to be fed, a scraper blade arranged above the block for movement toward and away from the same, a vertically arranged pole, a suspension element attached thereto, a horizontally arranged resilient bar having one end suspended from the suspension element and its opposite end rigidly attached to the scraper blade, and means for flexing the bar whereby to move the scraper blade away from the block, the latter being adapted to be released to permit the bar to return to normal position which rocks the scraper blade into engagement with the material and resiliently holds the same thereagainst.

the work block, the latter being moved toward the work block and resiliently held thereagainst upon release of the foot-operated member.

5 7. In a device of the character described, a work block, a scraper blade having one end pivoted to swing about a horizontal axis toward and away from the block, a resilient bar connected with one end of the scraper 10 blade, a suspended flexible element, a stirrup connected with the opposite end of the resilient bar, a threaded element connected with the stirrup and suspended element whereby to regulate the tension of the 15 resilient bar, and means whereby to bow the resilient bar whereby to raise the scraper blade from the block, the scraper blade being returned into engagement with the block

upon return of the resilient bar to its normal position.

8. In a device of the class described comprising a work block, a vertical member carried thereby, a scraper blade pivoted to the vertical member to swing about a horizontal axis, a channel shaped member formed with 25 one end of the scraper blade, a resilient bar having one end engaged in the channel shaped member and its opposite end supported, means whereby to bow the resilient bar to swing the scraper blade away from 30 the work block, the latter being returned into engagement with the block and resiliently held thereagainst upon release of said means.

ANTONIO S. HERNANDEZ.
